POODLE SWEATER OR SIMILAR ARTICLE

Eleanor Bacon, Los Angeles County, Calif.

Application August 19, 1955, Serial No. 37,581

Term of patent 14 years

(Cl. D38—10)

I claim:

The ornamental design for a poodle sweater or similar article, as shown and described.
